G. H. JUNG, JR.

ARCH SUPPORT

Filed Jan. 7, 1921

INVENTOR.

George H. Jung Jr.,
BY

Walter F. Murray
ATTORNEY.

UNITED STATES PATENT OFFICE.

GEORGE H. JUNG, JR., OF CINCINNATI, OHIO.

ARCH SUPPORT.

Application filed January 7, 1921. Serial No. 435,727.

To all whom it may concern:

Be it known that I, GEORGE H. JUNG, Jr., a citizen of the United States of America, and resident of Cincinnati, in the county of 5 Hamilton and State of Ohio, have invented a new and useful Improvement in an Arch Support, of which the following is a specification.

An object of my invention is to provide 10 an arch supporting pad that is readily adjustable to permit the accommodation of the pad to the individual case, and that will permit adjustment of the pad in such wise as is necessary and proper in view of the 15 development of the case to which applied.

These and other objects are attained by the means described herein and disclosed in the accompanying drawing in which:—

Fig. 1 is a side view of a device embodying my invention mounted on the foot of a patient and encased within a shoe, part of which is broken away.

Fig. 2 is an inverted plan view of a collapsed device embodying my invention.

Fig. 3 is a perspective view of the device shown in Fig. 2 in the form assumed thereby when ready to be applied to a patient's foot.

My invention comprises an endless elastic 30 band A having a tapered strip a mounted thereon so as to form a tapered pocket a' between the band and the strip. The pocket may be formed in any way but is preferably formed by sewing the tapered strip upon the 35 lower side or bottom of the band. The strip is also elastic. The band and strip are elastic transversely of a patient's foot when applied. The pocket need not be made tapered but can be varied to meet specific cases 40 requiring special treatment. A pad B is adapted to engage in the pocket and can be

adjusted in regard thereto so that more or less of the pad may extend from the pocket. The pad is preferably made of felt and is tapered, the sides thereof converging in 45 parallelism with the sides of the pocket. The pad can be made in other than tapered form but is so shown because in the majority of cases, requiring supporting of the patient's arches, it has been found that the 50 tapered pad accomplishes the desired result, besides conforming to and fitting into the form of the foot. This construction provides support immediately below the interior arch because the wide part of the pad is 55 disposed at that place, and the rearwardly tapered form thereof provides a gradual conforming to the patient's foot.

By adjusting the pad in the pocket the support is extended to various and different 60 muscles and parts of the arch, permitting proper treatment of the arches. As the patient improves the pad can be gradually moved backward into the pocket, thereby withdrawing the support from the arch in a 65 gradual manner. The transverse elasticity of the band and the strip serve to bind the pad in the pocket at its adjusted position.

What I claim is:

A transverse arch support comprising an 70 elastic band constructed to embrace a foot, an elastic strip secured to the band in such manner as to form a pocket opening in a direction transverse to the band, both band and strip being elastic transversely of the 75 foot as applied, and a pad engaged in the pocket.

In testimony whereof, I have hereunto subscribed my name this 4th day of January, 1921.

GEORGE H. JUNG, JR.
